UNITED STATES PATENT OFFICE.

THOMAS DEE, OF RANDOLPH, MASSACHUSETTS.

SPRING-HEEL.

933,422.

Specification of Letters Patent. Patented Sept. 7, 1909.

Application filed March 12, 1909. Serial No. 483,007.

To all whom it may concern:

Be it known that I, THOMAS DEE, of Randolph, in the county of Norfolk and State of Massachusetts, have invented certain new and useful Improvements in Spring-Heels, of which the following is a specification.

This invention has for its object to provide a boot or shoe heel having a yielding cushion of simple and durable construction adapted to effectively cushion the shocks and jars incidental to walking, and to be readily attached to and removed from the heel, so that the cushion may be readily removed and renewed when worn out.

15 The invention consists in the improvements which I will now proceed to describe and claim.

Figure 1 represents a bottom view of a heel provided with a socket in accordance with my invention, adapted to receive a detachable heel cushion. Fig. 2 represents a section on the line 2—2 of Fig. 1. Fig. 3 represents a side view of the cushion removed from the heel. Fig. 4 represents a view similar to Fig. 2, showing the cushion in section and engaged with the heel. Fig. 5 represents a perspective view of the bushing shown in Figs. 1, 2 and 4.

The same reference characters indicate the same parts in all the figures.

In carrying out my invention, I form in the body of a boot or shoe heel 12 a circular cavity or socket adapted to receive the cushion hereinafter described. Said socket is preferably formed by cutting out circular pieces from the lifts, of which the heel is composed, and inserting in the cavity thus formed a tubular sheet metal bushing 13, which closely fits the cavity so that it may be retained therein by friction or otherwise. The bushing is provided at its inner end with coupling members, which are here shown as an open hook 14 and a closed loop 15. The said coupling members are adapted to be detachably engaged with a cushion which includes a helical wire spring 16 formed to enter the bushing, the inner end portion of the spring being tapered or wedge-shaped, as indicated at 17, and so formed that it is adapted to enter the hook 14 and loop 15 by imparting a rotary movement to the spring when it has been inserted in the bushing, the outer end of the portion 17 of the spring first entering the hook and then the loop, so that, when the

spring has been rotated to a sufficient extent, its inner end portion will be engaged with the hook and loop as indicated in Fig. 4. The spring is thus detachably engaged with the bushing and with the heel, its disengagement from the heel being effected by rotating it backwardly until the inner portion of the spring is withdrawn from the hook and loop. The cushion also includes a head 18 formed to closely fit and move in the mouth of the bushing, the head being preferably a circular block, of rubber or other suitable elastic material impervious to dirt and water, provided with a reduced inner portion 19 of smaller diameter than the head and adapted to be screwed into the convolutions of the outer portion of the spring, the said reduced portion being firmly grasped by the spring so that the rubber head 18 and the spring 16 constitute a two-part cushion, the parts of which are rotatable in unison to apply the cushion to the heel and remove it therefrom. The head 18 normally projects from the socket or bushing, as indicated in Fig. 4, and is adapted to move in and out, and to prevent the admission of mud and dirt into the socket, the head having a close sliding fit on the inner surface of the socket.

It will be seen that the resilience of the cushion is due in part to the resilience of the rubber head and in part to the resilience of the spring 16. When the head has become worn, the two-part cushion may be removed from the socket as one part, by a backward rotation, and the head may then be unscrewed from its engagement with the spring and a new head substituted for it.

It is obvious that the coupling members 14 and 15 may be secured within the socket in any other suitable way, the bushing 13 being omitted, although the bushing is preferable. It will also be seen that the cushion may be placed on the market as an article of manufacture so that owners of boots or shoes, the heels of which are provided with the coupling members, may supply themselves with cushions to replace those that have been worn out. It will further be seen that the bushing and the cushion may be supplied as a heel attachment to boot and shoe manufacturers.

The open form of the hook 14 facilitates the entrance of the inner end of the spring into it, the said end being first introduced into the hook 14, which so guides the ad-

vancing end that it readily enters the closed loop 15. The wedge form of the end portion 17 of the spring enables it to be firmly engaged by friction with the closed loop 15, 5 so that when said portion is forced forward into said loop, it is secured against liability of accidental backward rotation.

The head 18 being of rubber and projecting below the tread of the heel, constitutes 10 a non-slipping tread, the spring constituting a resilient shank the inner end portion of which constitutes a coupling member.

I claim:

1. A heel having a socket, a two-part cushion composed of a rubber head having a sliding fit in said socket, and adapted to exclude dirt therefrom, and a helical spring the outer portion of which is firmly engaged with the head, so that the spring and head 20 are rotatable as one part, the head being separable from the spring, and the inner portion of the spring projecting inwardly from the head, and fixed coupling means at the inner end of the socket, the inner end 25 portion of the spring being engageable with and detachable from said coupling means by a rotary movement of the two-part cushion.
2. A heel having a socket, a rubber cushion head having a sliding fit in the socket and movable lengthwise thereof, said head being provided with an integral compressible inner portion of smaller diameter than the head, a helical spring the outer convolutions of which surround and compress said inner 30 portion, whereby the head and spring are connected to form a two-part cushion, the parts of which are rotatable in unison, the inner convolutions projecting inwardly from the head, and fixed coupling members at the 35 inner end of the socket, with which the inner end portion of the spring is engageable by a rotary movement of the two-part cushion to detachably secure the same to the heel,

said head closing the mouth of the socket and excluding dirt.

3. A heel having a socket, a rubber cushion head having a sliding fit in the socket and movable lengthwise thereof, said head being provided with an integral compressible inner portion of smaller diameter than the head, a helical spring the outer convolutions of which surround and compress said inner portion, whereby the head and spring are connected to form a two-part cushion, the parts of which are rotatable in unison, the inner convolutions projecting inwardly from the head, and fixed coupling members at the inner end of the socket, with which the inner end portion of the spring is engageable by a rotary movement of the two-part cushion to detachably secure the same to the heel, the inner end of the spring being wedge-shaped whereby it is adapted to frictionally engage one of said coupling members.

4. A two-part heel cushion comprising a rubber head forming the tread portion of the cushion, and provided with a reduced inner portion, and a helical spring forming the shank portion of the cushion, the outer convolutions of the spring being screwed upon the reduced inner portion of the rubber head, so that the two parts are adapted to be rotated in unison, and are separable from each other, the spring projecting from the inner portion of the head, so that its inner 70 end portion constitutes a coupling member adapted to be engaged with a complementary coupling member in a heel, by a rotary movement of the cushion.

In testimony whereof I have affixed my signature, in presence of two witnesses.
